UNITED STATES PATENT OFFICE.

MILES HANSON, OF SHEBOYGAN, WISCONSIN.

BLACKING-STAND.

SPECIFICATION forming part of Letters Patent No. 443,441, dated December 23, 1890.

Application filed October 3, 1890. Serial No. 366,924. (No model.)

To all whom it may concern:

Be it known that I, MILES HANSON, a citizen of the United States, residing at Sheboygan, in the county of Sheboygan and State of Wisconsin, have invented certain new and useful Improvements in Blacking-Stands; and I do hereby declare the following to be a full, clear, and exact description of the invention, such as will enable others skilled in the art to which it appertains to make and use the same.

This invention relates to blacking-stands, and has for its object to provide a simple and compact device to fill the long-felt want in private families and by individuals, which will be portable, light, neat, and at the same time occupy a minimum amount of space and afford a rest for the foot, a bracket for the blacking, and a shelf for the brushes, the latter also serving as a brace between the legs.

20 A further object of the invention is to have the bracket which supports the blacking automatic in its action, opening when the foot is placed on the foot-rest and closing after the pressure of the foot is removed.

25 The improvement consists of the novel features and the peculiar construction and combination of the parts, which will be herein-after more fully described and claimed, and which are shown in the annexed drawings, in 30 which—

Figure 1 is a perspective view of a blacking-stand embodying my invention, showing the operation of the presser-bar and the blacking-bracket by dotted lines. Fig. 2 is a cross-section of the foot-rest, showing the means for operating the blacking-bracket. Fig. 3 is a bottom perspective view, parts being broken away, of the foot-rest, showing the returning-spring and the cam-head for operating the 35 blacking-bracket, the latter being partly open. Fig. 4 is a front view of the presser-bar detached. Fig. 5 is a perspective view of a modification. Fig. 6 is a top plan view of the blacking-bracket. Fig. 7 is a detail section showing the relative arrangement of the presser-bar and the returning-spring for the bracket.

40 The stand comprises the foot-rest A, which is mounted on the legs B B, the bracket C, and the shelf D. The bracket C is pivoted at one end to the under side of the foot-rest and is recessed to receive the blacking, the projec-

tion in the rear of the pivot engaging with the stop E, limiting the movement of the said bracket in one direction. The under side of the foot-rest is cut away opposite the recess 55 in bracket C to give clearance for the blacking on the bracket and prevent the same binding between the bracket and the foot-rest on the latter closing. The foot-rest approximates the contour of the sole of the foot and is the 60 top of the stand, the legs being secured directly thereto. The legs spread at their lower ends to give stability to the stand, and are braced by the cross-bars b and the shelf D, the latter being secured to the cross-bars and 65 having the side pieces d, which form guards to retain the brush in place on the shelf.

The bracket C in Fig. 5 is designed to be opened and closed by hand; but in the form shown in Fig. 1 it is automatic in its action, 70 opening when the pressure of the foot is placed upon the stand and closing when the foot is removed. The latter construction is preferred, because of the automatic action of the bracket C.

75 The presser-bar F is provided with the stem f, which terminates in the cam-head f', that is adapted to ride upon the rear extension c of bracket C and turn the said bracket on its pivot when the presser-bar is depressed. The 80 cam-head curves in its circumferential length, the center of the curve being coincident with the pivot-connection of the bracket C with the foot-rest A. When the presser-bar is elevated, the cam-head f' enters a curved slot g 85 in the foot-rest, being limited in its upward movement by the pin h, which is projected across the said slot. The presser-bar is elevated by the spring G, which is mounted on the stem f, and which obtains a bearing on 90 the under side of the presser-bar F and on the bottom of the recess g', which is formed in the foot-rest at the inner end of the slot g. When the bar F is depressed, the spring G is compressed within this recess g'. The spring 95 H, which is mounted on the pivot I, that connects the bracket C with the foot-rest A, is secured at one end to the bracket C and at its other end to the foot-rest A, and serves to close the bracket when the pressure of the 100 foot is removed from the presser-bar F. The presser-bar is depressed to conform to the

curvature of the shank of the shoe in cross-section.

The operation of the invention is manifest from the foregoing description. However, it 5 may be well to state that the presser-bar F is elevated a sufficient distance above the foot-rest to be engaged by the foot before the latter comes squarely upon the foot-rest and depress the same sufficiently far to effect an 10 opening of the bracket C to permit access to the blacking, the bracket being opened by the instrumentalities hereinbefore specified. When the pressure of the foot is removed, the spring G, reacting, will elevate the presser-bar and the spring H will close the bracket C. 15

Having thus described my invention, what I claim, and desire to secure by Letters Patent, is—

1. A blacking-stand comprising a top or 20 foot-rest conforming to and approximating the contour of the sole of the foot and having its under side cut away to form a recess, and mounted on legs which spread at their bottom, a blacking supporting bracket pivoted 25 to the under side of the top, a stop to limit the movement of the said bracket, and a brush-shelf secured to the legs near their lower ends and bracing the said legs, substantially as described.

2. In a blacking-stand, the combination, 30 with the foot-rest and a bracket, as C, of a presser-bar and means between the presser-bar and the said bracket for projecting the latter when the said presser-bar is depressed, substantially as described.

3. In a blacking-stand, the combination,

with the foot-rest and a bracket, as C, of the presser-bar constructed to project the bracket when pressed upon, and a spring for closing the said bracket, substantially as described. 40

4. In a blacking-stand, the combination, 45 with the foot-rest and the bracket, of the presser-bar constructed to project the bracket when pressed upon, and springs, one for elevating the presser-bar when relieved of pressure and the other for closing the bracket, substantially as specified.

5. In a blacking-stand, the combination, 50 with the foot-rest and the bracket pivoted to the foot-rest, of the presser-bar having a shank which terminates in a cam-head, which cam-head curves in its circumferential length and is adapted to engage with and open the bracket when the said presser-bar is depressed, substantially as described.

6. In a blacking-stand, the combination, 55 with the foot-rest and the bracket pivoted to the foot-rest, of the presser-bar having a shank which terminates in a cam-head that curves in its circumferential length, and which is 60 adapted to engage with the said bracket and open the same when the presser-bar is depressed, and which when elevated enters a curved slot provided in the foot-rest, substantially as described.

In testimony whereof I affix my signature in presence of two witnesses.

MILES HANSON.
